INVENTOR

BY *Victor J. Evans*

ATTORNEY

WITNESS

J. E. Cole

UNITED STATES PATENT OFFICE.

MARTIN JENSEN, OF CHERAW, SOUTH CAROLINA.

HINGE.

Application filed July 19, 1922. Serial No. 576,066.

To all whom it may concern:

Be it known that I, MARTIN JENSEN, a citizen of the United States, residing at Cheraw, in the county of Chesterfield and 5 State of South Carolina, have invented new and useful Improvements in Hinges, of which the following is a specification.

My present invention has reference to a hinge construction, primarily adapted for 10 use in connection with casement windows, but, of course, susceptible to other uses, and has for its object to produce in a hinge, means for preventing the accidental opening 15 or closing of the pivotally connected plates constituting the hinge.

A further object is to arrange in the barrel 20 end of plates constituting a hinge, sleeve members which rest between certain of the barrels, which have their confronting ends provided with interengaging teeth which 25 are grooved to engage the inner edges of the respective hinge plates, which are spring influenced toward each other, and which are sustained on the hinge by the pintle received in the barrels of the hinge.

The foregoing, and other objects which 30 will present themselves as the nature of the invention is better understood, may be accomplished by a construction, combination 35 and operative association of parts such as is disclosed by the drawing which accompanies and forms part of this application.

In the drawing:—

Figure 1 is a plan view of a hinge in accordance with this invention.

Figure 2 is a sectional view on the line 2—2 of Figure 1.

Figure 3 is a sectional view on the line 3—3 of Figure 2.

Figures 4 and 5 are views of the clutch sleeve members, looking toward the toothed ends thereof.

In general, the hinge 1 is constructed in a manner similar to that of the ordinary 45 hinges, the hinge comprising plates 1 and 2 which have their confronting edges provided with spaced barrels 3 designed for interengagement between each other, and through these barrels there is passed the usual pintle 4.

Two of the confronting barrels, one on each of the plates 1 and 2 are spaced a distance away from each other, and the inner

edges of the plates opposite the referred to narrow barrels are notched, as at 5 and 6 respectively.

Designed to pass through the notch 5 of the plate 1 is a sleeve member 7. The sleeve has a groove 8 that engages the inner edge of the said plate 1. The sleeve is sustained on the hinge by the pintle 4 passing through the bore thereof. The sleeve 7 has a socket portion 9 communicating with its bore but of a larger area than that of the bore, and in this socket there is received a helical spring 10 which, of course, surrounds the pintle 4 and which also contacts with the narrow barrel on the plate. Passing through the notch 6 of the plate 2 there is a shorter sleeve 11, the sleeve having a groove 12 that receives therethrough the inner edge of the plate 6. The confronting faces of the sleeves 7 and 11 are provided with interengaging ratchet teeth 13 and 14 respectively. The spring influences the sleeves toward each other so that the ratchet surfaces thereof will be in interengagement. The sleeve being locked to the respective plates of the hinge prevent a free swinging or accidental movement of either of the plates with respect to each other on the pintle 4.

Having described the invention, I claim:—

The combination with a hinge including plates having barrels on their inner ends, and a pintle passing through the barrels for connecting the plates, two of the confronting barrels, one on each of the respective plates being spaced from each other, and the inner edges of the said plates being notched, a pair of sleeves having each a longitudinal groove designed to be passed through the notches of the plates and the grooves thereof moved to receive the edges of the plates therein, said sleeves being sustained on the hinge by the pintle thereof, said sleeves having their confronting edges provided with interengaging teeth, and spring means surrounding the pintle and exerting a tension between one barrel of the hinge and one sleeve for forcing the teeth of the sleeves into engagement with each other.

In testimony whereof I affix my signature.

MARTIN JENSEN.
